INVENTOR.

Thomas Shaw.

United States Patent Office.

THOMAS SHAW, OF PHILADELPHIA, PENNSYLVANIA.

Letters Patent No. 70,752, dated November 12, 1867.

IMPROVEMENT IN COG-CHAINS.

The Schedule referred to in these Letters Patent and making part of the same.

TO ALL WHOM IT MAY CONCERN:

Be it known that I, THOMAS SHAW, of the city and county of Philadelphia, Pennsylvania, have invented a new and improved Mode of Constructing Chain; and I hereby declare the following to be a full, clear, and exact description of the same, reference being had to the accompanying drawings, and the letters of reference marked thereon.

My invention consists in the shaping of a link so that it can be cast into shape, and in constructing it of such a shape that one link will lock into another and form a complete cog-chain, without riveting or forging, as hereafter described.

In order to enable others to use and practise my invention, I will proceed to describe its construction and operation.

On reference to the accompanying drawings, which form a part of the specification, the sketch represents a view of three links of said chain, of which—

Figure 1 is a back view, or the part which would come in contact with a cog-wheel.

Figure 2 is an edge view of the links, showing their general shape, and how they lock into each other.

Similar letters refer to similar parts.

a represents the links, of which *b* is the bearing part, a broad piece of metal terminating in a hook at each end. *c* is a rib, projecting from the middle of one side of said hooked part *b*, and fits loosely into a corresponding slot, *d*, of another link. Said rib *c* has on its outer edge a part that projects beyond, forming a right-angled corner, as indicated in fig. 2. The object of rib *c* and its projecting corner is, that the rib fitting into slot *d* prevents the links from sliding apart laterally, and that the projecting corner is to prevent the links from unlocking when they are so far bent on the joint as to cause the links to be arrested at this point. The further object of said rib *c* is that the several ribs of link of chain will fit into a groove in the middle of the chain cog-wheel, and thus prevent its slipping off the wheel.

The object of this chain is cheapness, strength, and durability.

It will be observed that they can be cast of iron, steel, or brass, and that they need simply be hooked together when cast to form the chain, and that they will not unhook themselves when passing over pulleys.

The shape might be slightly modified without any alteration of the result.

What I claim, and desire to secure by Letters Patent, is—

The chain-links, as constructed, for the purpose specified.

THOMAS SHAW. [L. S.]
